UNITED STATES PATENT OFFICE.

JOHN K. PAMEYER, OF TACOMA, WASHINGTON.

PALETTE.

Application filed September 12, 1921. Serial No. 500,206.

To all whom it may concern:

Be it known that I, JOHN K. PAMEYER, a citizen of the United States, residing at Tacoma, in the county of Pierce and State 5 of Washington, have invented a new and useful Palette, of which the following is a specification.

By way of explanation, it may be stated that sign writers and others using a palette, 10 are compelled to stoop or move frequently, in order to dip the paint brush into the paint pot or cup. The foregoing being understood, one object of the invention is to provide a palette on which a paint cup may be 15 mounted detachably, and removably, thereby rendering it unnecessary for the person using the palette to stoop, stretch, or assume any other inconvenient position in order to reach a paint cup.

Another object of the invention is to provide novel means whereby the palette and the mahlstick may be carried conveniently 20 in the hand, the mahlstick supporting the palette.

It is within the province of the disclosure to improve generally and to enhance the utility of devices of that type to which the invention appertains.

With the above and other objects in view, 30 which will appear as the description proceeds, the invention resides in the combination and arrangement of parts and in the details of construction hereinafter described and claimed, it being understood that, with 35 in the scope of what is claimed, changes in the precise embodiment of the invention shown can be made without departing from the spirit of the invention.

In the accompanying drawings:—

Figure 1 shows in perspective, a device 40 constructed in accordance with the invention; Figure 2 is a bottom plan of the palette; Figure 3 is a cross section on the line 3—3 of Figure 2.

In carrying out the invention there is 45 provided a palette 1 which may be of any desired size or shape, depending upon the nature of the work which is to be done. The palette 1 may be fashioned from any 50 desired material. If it is made from aluminum, it may be cleaned readily. A strip 2 extends transversely of the palette 1 and is located on the under surface thereof, the 55 ends 5 of the strip engaging the edges of the palette 1 for additional security and strength. Securing elements 3 attach the

strip 2, adjacent to its ends, to the palette 1. The strip 2 is bent to form sockets 6 and 7, located relatively near to the longitudinal edges of the palette 1, the sockets ordinarily 60 being disposed at an angle to each other, as shown in Figure 2. Intermediate the sockets 6 and 7 the strip 2 is attached by a securing element 4 to the palette 1. In one of its longitudinal edges the palette 1 has a notch 65 or seat 9, disposed adjacent to the socket 7.

The numeral 10 denotes a paint cup, and in this connection, it is to be understood that as many cups as desired, may be provided. The cup 10 rests on the palette 1 70 adjacent to one edge thereof, and is provided with a resilient clip 11, extended beneath the palette and gripping the palette, the construction being such that, although the cup 10 is held on the palette, the cup 75 may be adjusted to any desired position, around the edge of the palette.

In practical operation, the thumb 12 of the hand of the operator is inserted in the socket 6, the index finger 14 being inserted 80 in the socket 7. The mahlstick 15 is extended between the index finger 14 and the third finger 16. The mahlstick 15 is received in the seat 9, and thus, the palette is supported not only by the hand of the operator, 85 but upon the mahlstick, as well.

It is obvious that the construction of the device is such that the person using the palette will always have at hand, on the palette, a supply of paint or pigment, the operator having no occasion to reach for a remote paint receptacle.

What is claimed is:—

1. In a device of the class described, a palette provided in one edge with a seat 95 for the reception of a mahlstick; and sockets extended downwardly from the lower surface of the palette and spaced apart transversely of the palette, one of the sockets being located adjacent to the seat. 100

2. In a device of the class described, a palette provided in one edge with a seat for the reception of a mahlstick; and sockets extended downwardly from the lower surface of the palette and spaced apart transversely of the palette, one of the sockets being located adjacent to the seat, and one socket being located at an angle to the other socket. 105

3. In a device of the class described, a 110 palette; a strip extended transversely of the palette and overlapped at its ends on

the edges of the palette, securing means uniting the strip with the palette adjacent to the ends of the strip, and a securing means uniting the strip with the palette intermediate the ends of the strip, the strip being carried downwardly adjacent to its ends, to form finger-receiving sockets.

In testimony that I claim the foregoing as my own, I have hereto affixed my signature in the presence of two witnesses.

JOHN K. PAMEYER.
